(57) **CLAIM**

The ornamental design for an interactive doll, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front isometric view of my new, original, and ornamental design;

FIG. 2 is a rear isometric view;

FIG. 3 is a front elevational view;

FIG. 4 is a rear elevational view;

FIG. 5 is a left side elevational view (the right side being a mirror image thereof);

FIG. 6 is a top plan view; and,

FIG. 7 is a bottom view.

The features of the interactive doll shown in broken lines are for illustrative purposes only and form no part of the claimed design.
